PACKING APPARATUS

Dwight W. Wadsworth and William A. Breckon,
Fennville, Mich.Application November 21, 1932
Serial No. 643,698

30 Claims. (Cl. 226—17)

The main objects of this invention are:

First, to provide an improved packing apparatus or device for the packing of fruits, vegetables and the like which greatly expedites and lessens the 5 labor as compared with apparatus heretofore used.

Second, to provide an apparatus for use in the packing of fruits, vegetables and the like by means of which the packing with a uniformly arranged top layer is greatly facilitated.

Third, to provide an apparatus of this character which may be employed with little likelihood of injuring the product which is being packed.

Objects relating to details and economies of 15 our invention will appear from the description to follow. The invention is defined and pointed out in the claims.

A structure which is a preferred embodiment 20 of our invention is illustrated in the accompanying drawings, in which:

Fig. 1 is a perspective view of our improved packing apparatus in operative relation to a receptacle or basket of the straight side flat bottom type, the apparatus being in the position after 25 the packing operation is completed.

Fig. 2 is a fragmentary plan view of the parts as shown in Fig. 1.

Fig. 3 is a vertical section on a line corresponding to the broken line 3—3 of Fig. 2, the contents 30 of the packing product being conventionally indicated by dotted lines.

Fig. 4 is a fragmentary vertical view illustrating certain steps of the packing operation.

Fig. 5 is a detail fragmentary sectional view 35 corresponding to that of Fig. 4 illustrating another step.

Fig. 5A is a fragmentary section corresponding to that of Fig. 5 illustrating a step in the manipulation of the apparatus succeeding that shown in 40 Fig. 5.

Fig. 6 is an enlarged fragmentary sectional view illustrating still further steps in the manipulation of the apparatus, the section being taken on a line corresponding to line 6—6 of Figs. 2 and 7. 45

Fig. 7 is an enlarged detail section on line 7—7 of Fig. 6.

Fig. 8 is an enlarged detail section on line 8—8 of Fig. 2.

Fig. 9 is a perspective view of one of the removable segmental wall members.

Fig. 10 is an enlarged inverted perspective view of the facing tray bottom member.

Fig. 11 is a fragmentary view in section on line 11—11 of Fig. 6.

55 Fig. 12 is an enlarged detail section on a line

corresponding to line 12—12 of Figs. 6 and 13 showing details of one of the handles.

Fig. 13 is an enlarged detail section on a line corresponding to line 13—13 of Figs. 6 and 12.

Fig. 14 is a detail section on a line corresponding to line 14—14 of Fig. 13.

Fig. 15 is a fragmentary view illustrating the arrangement of the facing band or liner in the apparatus.

Fig. 16 is an enlarged detail section on a line 65 corresponding to line 16—16 of Fig. 2.

In the accompanying drawings, 1 represents a basket of the straight side flat bottom type which is a type now in extensive use. While we have shown our apparatus in connection with this type 70 of basket, it is adapted for use without change in the standard type of round bottom bushel basket. 2 represents fruit or other product to be packed in filling the basket.

Our apparatus, in the embodiment illustrated, 75 comprises an annular frame 3 having an inwardly projecting flange 4, the upper edge 5 of the frame being preferably tapered. This annular frame member is tapered upwardly. The concavo-convex bottom plate 6 loosely fits or is floatingly 80 mounted within this frame and is adapted to rest on the flange 4 thereof.

The bottom plate is provided with angled clips 7 which overhang the flange, serving as stops or supports for the bottom when the apparatus is 85 in inverted position. The bottom plate has a central opening 8 adapted to receive the disk 9 secured centrally to the flexible diaphragm 10.

This diaphragm 10 has a reinforcing beading 90 11 at its edge and is secured to the periphery of the bottom plate 6 by means of U-shaped clips 12. This diaphragm is adapted to rest upon and be supported by the bottom 6 as is shown in Figs. 4 and 5A, for example, or it may be adjusted to the position shown in Fig. 5 to receive and facilitate the arrangement of the facing layer. The diaphragm plate is provided with a rabbeted or shouldered edge 13 adapted to rest in the rabbeted or shouldered edge of the opening in 95 the bottom 6.

The facing diaphragm is yieldingly held in the position shown in Fig. 5 to present a concaved surface for the facing layer or in its collapsed position as shown in Fig. 5A and in other figures by means of springs 15 arranged on the links 16, these links being pivoted to the central lug 17 of the plate 13 and slidably and pivotally engaged with lugs 18 on the bottom 6, one end of the springs being supported by these lugs and the other engaging thrust collars 19 on the links. As 100 105 110

the diaphragm plate is shifted from its raised to its lowered position the pivot 20 for the links to the lug 17 passes through a plane of the supporting lugs for the outer ends of the links so that the links act as a toggle for holding the diaphragm in both collapsed and erected position. A flexible finger piece or strap 21 is provided for manipulating the diaphragm.

As a preliminary step to arranging the facing layer, the diaphragm is pulled to its upper or crown position, as illustrated in Fig. 5. The facing layer and retainer may then be quickly and easily arranged beginning at the outside and working inwardly. When the facing layer has been placed, the diaphragm is pushed down to the position shown in Figs. 4 and 5A.

In the accompanying drawings, we illustrate the employment of a facing band or liner 22 which is usually of heavy paper and provided with an in-turned notched edge, as shown in Fig. 15. To assist in holding this band in position, the frame is provided with a plurality of spring fingers or holders 23 which are secured at their lower ends adjacent the lower ends of the frame and project through openings 24 provided therefor in the flange 4, (see Fig. 12).

As stated, the bottom is floatingly mounted on the annular frame, adjustable stops 25 being provided, however, to limit its movement. By means of the adjustment of these stops, the extent of the projection of the facing layer from the receptacle can be considerably varied which is a desirable feature to different types of covers and the appearance desired in the package or receptacle. The frame is provided with oppositely projecting ears 26 to which the handles 27 are pivoted at 28.

The handles 27 are, in the embodiment illustrated, U-shaped, the knob-like hand pieces 29 being secured to the outer side thereof, and being conveniently grasped for lifting and allowing the turning of the apparatus through the action of gravity to an upright position as will be pointed out later.

The side walls 30 are segmental and complementary and detachably secured to the frame, the walls having notched lugs 31 positioned to lie at the sides of the ears 26 when the walls are assembled on the frame. The handles are provided with keepers or latches 32 pivotally connected to the handles at 33 and carrying pins 34 engageable with the notches in the lugs or keepers 31, the movement of these latches being controlled by the pin's engagement with the slots 35 in the handle ears so that with the side walls in assembled position relative to the frame, the handles may be swung inwardly to engage the latches thereof with these keepers, thereby locking the side wall members to the frame.

The bottom 6 is provided with toothed keepers 36 which project through slots 37 in the frame and between the side walls to be engaged by the handles 38 of the basket or receptacle 1.

As the handles carry the entire load in reversing the apparatus after the packing has been completed, a cross or tie rod 39 is provided for the frame in alignment with the handles.

Having described the structure, we will now describe the manner of using. Assuming that the side walls are detached, the apparatus is placed in the position shown in Fig. 5 and the facing diaphragm pulled up to the position there shown by grasping the strap 21. The facing band 22 may be positioned in supporting engagement with the fingers 23 either before or after the adjustment of the facing diaphragm. The

facing layer is then arranged with the diaphragm in its crown position, as shown in Fig. 5, and the diaphragm may be pushed downwardly to the position shown in Fig. 5A which serves to firmly hold this facing layer in position, the upper edge of the frame preferably projecting slightly below the center line of the outer layer of fruit or other product being packed. The side wall members are then put in position and the handles swung inwardly to lock them in position. The side walls form a receptacle which is then filled. The receptacle to be packed is then slipped over this packing receptacle and the handles 35 thereof engaged with the teeth of the keepers 36, there being a series of these teeth so that a ratchet action is had as the receptacle 1 is pushed down over the packing receptacle. With the basket or receptacle to be packed thus locked to the filling packing receptacle, the whole is lifted as a unit by grasping the handles and, owing to the position of the handles, gravity acts to reverse the apparatus. The handles are then swung outwardly to release the side wall members and they are pulled out, being provided with grips or hand pieces 40 for convenient manipulation. It will be noted that these side wall members are pulled out at an angle corresponding to the angle of the walls of the receptacle so that the contents are not likely to be injured or bruised by this step. The handles of the packed receptacle are then disengaged from the keepers 36 and the apparatus can be lifted off.

Our improved apparatus greatly expedites and lessens the labor in packing fruit and vegetables and enables the rapid placing of the facing which is very securely held during the packing operation so that it is not likely displaced and when the apparatus is removed from the packed receptacle the cover may be placed without rearranging any of the facing.

We have illustrated and described our improvements in an embodiment which we have found highly satisfactory. We have not attempted to illustrate or describe certain embodiments and adaptations which we contemplate as we believe that this disclosure will enable those skilled in the art to embody or adapt our improvements as may be desired.

Having thus described our invention, what we claim as new and desire to secure by Letters Patent is:

1. In a packing device, the combination of an annular frame having an inwardly projecting flange and opposed ears having segmental slots therein, said frame also having slots aligned with said ears, a concaved bottom floatingly mounted above said flange and having toothed receptacle handle keepers projecting through said slots in said frame, said bottom having lugs spaced therefrom and projecting below said flange for limiting the floating movement of the bottom relative to the frame, adjustable rests for said bottom, a facing diaphragm secured at its periphery to said bottom, a means acting to hold said diaphragm in crowned position or in its collapsed position on said bottom, removable segmental wall members having notched lugs positioned at the sides of said ears of said frame when the wall members are in assembled relation to the frame, handles pivotally mounted on said ears, and latches pivotally mounted on said handles and provided with pins adapted to engage said lugs on said wall members, said latch pins being disposed within

- said segmental slots in said ears whereby they are guided to wall lug engaging position.
2. In a packing device, the combination of an annular frame having opposed ears having segmental slots therein, said frame also having slots aligned with said ears, a concaved bottom floatingly mounted on said frame and having toothed receptacle handle keepers projecting through said slots in said frame, a facing diaphragm secured at its periphery to said bottom, a means acting to hold said diaphragm in crowned position or in its collapsed position on said bottom, removable segmental wall members having notched lugs positioned at the sides of said ears of said frame when the wall members are in assembled relation to the frame, handles pivotally mounted on said ears, and latches pivotally mounted on said handles and provided with pins adapted to engage said lugs on said wall members, said latch pins being disposed within said segmental slots in said ears whereby they are guided to wall lug engaging position.
3. In a packing device, the combination of an annular frame having opposed ears having segmental slots therein, said frame also having slots aligned with said ears, a concaved bottom floatingly mounted on said frame and having toothed receptacle handle keepers projecting through said slots in said frame, a facing diaphragm secured at its periphery to said bottom, a means acting to hold said diaphragm in crowned position or in its collapsed position on said bottom, removable segmental wall members having notched lugs positioned at the sides of said ears of said frame when the wall members are in assembled relation to the frame, handles pivotally mounted on said ears, latches pivotally mounted on said handles and provided with pins adapted to engage said lugs on said wall members, said latch pins being disposed within said segmental slots in said ears whereby they are guided to wall lug engaging position, and spring liner holder fingers mounted on said frame to project upwardly on the inner side thereof.
4. In a packing device, the combination of an annular frame having an inwardly projecting flange and opposed ears having segmental slots therein, said frame also having slots aligned with said ears, a concaved bottom floatingly mounted above said flange and having toothed receptacle handle keepers projecting through said slots in said frame, said bottom having lugs spaced therefrom and projecting below said flange for limiting the floating movement of the bottom relative to the frame, adjustable rests for said bottom, a facing diaphragm secured at its periphery to said bottom, said bottom having a central opening therein, a plate secured to said bottom and adapted to seat within said opening, a pair of opposed links pivotally mounted on said plate, said bottom having lugs with which said links are slidably and pivotally engaged, and springs arranged on said links and coacting therewith to provide a toggle acting to hold the diaphragm in its erected crowned position and also in its collapsed position.
5. In a packing device, the combination of an annular frame having opposed ears having segmental slots therein, said frame also having slots aligned with said ears, a concaved bottom floatingly mounted on said frame and having toothed receptacle handle keepers projecting through said slots in said frame, removable segmental wall members having notched lugs positioned at the sides of said ears of said frame when the wall members are in assembled relation to the frame, handles pivotally mounted on said ears, and latches pivotally mounted on said handles and provided with pins adapted to engage said lugs on said wall members, said latch pins being disposed within said segmental slots in said ears whereby they are guided to wall lug engaging position.
6. In a packing device, the combination of an annular frame having opposed ears having segmental slots therein, said frame also having slots aligned with said ears, a concaved bottom floatingly mounted on said frame and having toothed receptacle handle keepers projecting through said slots in said frame, removable segmental wall members having notched lugs positioned at the sides of said ears of said frame when the wall members are in assembled relation to the frame, handles pivotally mounted on said ears, latches pivotally mounted on said handles and provided with pins adapted to engage said lugs on said wall members, said latch pins being disposed within said segmental slots in said ears whereby they are guided to wall lug engaging position, and liner holder fingers mounted on said frame to project upwardly on the inner side thereof.
7. A packing device comprising an annular frame member having an inwardly projecting flange, a concaved bottom floatingly mounted above said flange and having toothed receptacle handle keepers projecting from said frame, said bottom having lugs spaced therefrom and projecting below said flange for limiting the floating movement of the bottom relative to the frame, adjustable rests for said bottom, a facing diaphragm secured at its periphery to said bottom, said bottom having a central opening therein, a plate secured to said bottom and adapted to seat within said opening, a pair of opposed links pivotally mounted on said plate, said bottom having lugs with which said links are slidably and pivotally engaged, and springs arranged on said links and coacting therewith to provide a toggle acting to hold the diaphragm in its erected crowned position and also in its collapsed position.
8. A packing device comprising an annular frame member having an inwardly projecting flange, a concaved bottom floatingly mounted above said flange and having toothed receptacle handle keepers projecting from said frame, said bottom having lugs spaced therefrom and projecting below said flange for limiting the floating movement of the bottom relative to the frame, and adjustable rests for said bottom.
9. A packing device comprising an annular frame member, a concaved bottom having a central opening therein, a facing diaphragm secured at its periphery to said bottom, a plate secured to said bottom and adapted to seat within said opening, a pair of opposed links pivotally mounted on said plate, said bottom having lugs with which said links are slidably and pivotally engaged, and springs arranged on said links and coacting therewith to provide a toggle acting to hold the diaphragm in its erected crowned position and also in its collapsed position.
10. A packing device comprising a frame member, a concaved bottom, a facing diaphragm secured at its periphery to said bottom, a pair of opposed links pivotally connected to said diaphragm, said bottom having lugs with which said links are slidably and pivotally engaged, and springs arranged on said links and coacting therewith to provide a toggle acting to hold the diaphragm in its erected crowned position and also in its collapsed position.

11. In a packing device, the combination of an annular frame, a bottom floatingly mounted on said frame and having receptacle handle engaging members on the outside of said frame, adjustable rests for said bottom, removable segmental wall members, and handles pivotally mounted on said frame and provided with latches for detachably securing said wall members in assembled relation on the frame. 80
12. In a packing device, the combination of an annular frame, a bottom having receptacle handle engaging members on the outside of said frame, removable segmental wall members, and handles pivotally mounted on said frame and provided with latches for detachably securing said wall members in assembled relation on the frame. 85
13. In a packing device, the combination of an annular frame, a bottom having receptacle handle engaging members on the outside of said frame, a facing diaphragm secured at its periphery to the periphery of said bottom, spring means acting to hold said diaphragm in crowned position or in collapsed position, removable segmental wall members, and handles pivotally mounted on said frame and provided with latches for detachably securing said wall members in assembled relation on the frame. 90
14. In a packing device, the combination of a frame provided with opposed handles, segmental wall members detachably secured to said frame, a concaved bottom, a facing diaphragm operatively associated with said bottom, and means for holding said diaphragm in crowned position and permitting the collapsing thereof, said bottom having receptacle handle engaging means. 95
15. In a packing device, the combination of a frame provided with opposed handles, segmental wall members detachably secured to said frame, and a concaved bottom. 100
16. In a packing device, the combination of a frame provided with opposed handles, segmental wall members detachably secured to said frame, a concaved bottom floatingly mounted on said frame, and adjustable rests for said bottom. 105
17. In a packing device, the combination of a frame, wall members, a concaved bottom floatingly mounted on said frame, adjustable rests for said bottom, a facing diaphragm operatively associated with said bottom, and spring means for holding said diaphragm in crowned position and permitting the collapsing thereof. 110
18. In a packing device, the combination of a frame, wall members, a concaved bottom, a facing diaphragm operatively associated with said bottom, and spring means for holding said diaphragm in crowned position and permitting the collapsing thereof, said spring means also acting to hold said diaphragm in collapsed position. 115
19. In a packing device, the combination of a frame having opposed ears, said ears having segmental slots therein, a bottom carried by said frame, segmental side wall members having notched lugs positioned at the sides of said ears when the side wall members are in assembled relation to the frame, handles pivotally mounted on said ears, and latches pivotally mounted on said handles and provided with pins adapted to engage said lugs on said wall members, said ears having segmental slots through which said pins are disposed whereby the latches are guided to lug engaging position. 120
20. In a packing device, the combination of a frame having opposed ears, a bottom carried by said frame, segmental side wall members having notched lugs positioned at the sides of said ears when the side wall members are in assembled relation to the frame, handles pivotally mounted on said ears, and latches pivotally mounted on said handles and provided with pins adapted to engage said lugs on said wall members, said ears having segmental slots through which said pins are disposed whereby the latches are guided to lug engaging position. 125
21. In a packing device, the combination of an annular frame, a bottom floatingly mounted on said frame, liner holder fingers mounted on said frame, wall members, handles pivotally mounted on said frame and provided with side wall engaging members, means actuated by said handles for securing said wall members to said frame, and means for detachably securing a receptacle to said bottom. 130
22. In a packing device, the combination of an annular frame, a bottom floatingly mounted on said frame, wall members, liner holder fingers mounted on said frame, handles pivotally mounted on said frame and provided with side wall engaging members, and means actuated by said handles for securing said wall members to said frame. 135
23. In a packing device, the combination of an annular frame, a bottom floatingly mounted on said frame, liner holder fingers mounted on said frame, segmental wall members, handles pivotally mounted on said frame and provided with side wall engaging members, and means actuated by said handles for securing said wall members to said frame. 140
24. In a packing device, the combination of a frame, a bottom floatingly mounted on said frame, segmental wall members, means for detachably securing said wall members to said frame, and means for detachably securing a receptacle to said bottom. 145
25. In a packing device, the combination of a frame, a bottom, segmental wall members, and means for detachably securing said wall members to said frame. 150
26. In a packing device, the combination of a frame, a bottom, liner holder fingers mounted on said frame, segmental wall members, and means for detachably securing said wall members to said frame. 155
27. In a packing device, the combination of a frame provided with opposed handles, a bottom, receptacle engaging members carried by said frame, a facing diaphragm secured at its periphery to said bottom, means for holding said diaphragm in crowned position, and segmental wall members detachably secured to said frame. 160
28. In a packing device, the combination of a frame provided with opposed handles, a bottom, receptacle engaging members carried by said frame, and segmental wall members detachably secured to said frame. 165
29. In a packing device, the combination of a frame, a bottom carried by said frame, a facing diaphragm secured at its periphery to said bottom, and segmental wall members detachably and independently secured to said frame whereby said wall members may be released to permit their independent withdrawal from a receptacle. 170
30. In a packing device, the combination of a frame provided with opposed handles, a bottom, and segmental wall members detachably secured to said frame by manipulation of said handles. 175
